CLAIM

The ornamental design for a dispenser for adhesive tape roll, as shown and described.

DESCRIPTION

FIG. 1 is a perspective view of a dispenser for adhesive tape roll showing my new design;

FIG. 2 is a top plan view thereof;

FIG. 3 is a front elevational view thereof;

FIG. 4 is a left side elevational view thereof;

FIG. 5 is a right elevational view thereof;

FIG. 6 is a bottom plan view thereof;

FIG. 7 is a rear elevational view thereof; and,

FIG. 8 is a perspective view of the front face thereof, shown separately for convenience of illustration.

The tape depicted by means of broken lines in FIGS. 2 and 3 has been shown for illustrative purposes only and forms no part of the claimed design.
